UNITED STATES PATENT OFFICE.

JAMES CONLON, OF PAWTUCKET, RHODE ISLAND.

TRANSPORTATION SYSTEM.

1,342,531.

Specification of Letters Patent.

Patented June 8, 1920.

Application filed October 30, 1918. Serial No. 260,328.

To all whom it may concern:

Be it known that I, JAMES CONLON, a citizen of the United States, residing at Pawtucket, in the county of Providence and State of Rhode Island, have invented new and useful Improvements in Transportation Systems, of which the following is a specification.

The object of the invention is to provide 10 a transportation system in which a car travels through a tubular construction which may be beneath the surface of the ground or may be constructed above the surface and be operated as an elevated railway.

15 A further object is to provide a structure of the type indicated through which the cars are designed to travel under fluid pressure, the pressure being supplied in the form of compressed air or steam, whichever may be 20 desired.

With the foregoing and other objects in view, the invention consists in the novel construction, combination and arrangement of elements hereinafter described and 25 claimed.

Figure 1 is a vertical longitudinal section of a portion of the apparatus constituting my invention, the car being shown, in elevation.

30 Fig. 2 is a top plan view of the parts shown in Fig. 1, portions being broken away and shown in section.

Fig. 3 is a diagrammatic transverse section and part elevation, indicating the motion 35 power plant and its relation to the tubular way or tunnel.

In carrying out my invention I build a 40 tubular construction comprising side members 10 and 12 and upper and lower walls 13 and 14 providing a bore which may be square or rectangular in cross section, the entire construction being rectangular in cross section if desired.

A plurality of inlets 16 are provided at 45 the required intervals, these inlets being in the top and bottom walls if desired, and having connection with inlet ducts 17 through which fluid is supplied under pressure for the purpose of propelling the cars, 50 one of which is shown conventionally and is designated 20. These cars may be of suitable construction and may be provided with means for effecting substantially close contact with the walls of the bore, without 55 producing unnecessary friction. For the purpose of supplying the propelling fluid

the inlet ducts 17 are connected with power plants along the line of the system at suitable intervals, these plants including boilers 25, steam engines 26 and air compressors 27, 60 and tanks 28 (see Fig. 3), so that the propelling fluid may be supplied in such form as may be desired under given conditions.

Gates or valves 18 may be located at frequent intervals, these valves opening in a 65 given direction under impact when the car approaches, so that the propelling fluid will exert its influence within a closed chamber comprising that section of the tube between the car at a given time and a given cutoff 70 device or gate. The inlet members may be deflected at an angle as shown as at 16 in order that the influence of the fluid may be more readily directed for producing the results required. It will of course be understood 75 that the system is operated with a plurality of tubes extending throughout the entire length thereof in parallel relation or in given instances be constructed as a belt line, in any event the cars will travel 80 in a given direction in each tube.

Rollers designated 21 may be located at frequent intervals in the tube, and a car coming in contact therewith will pass freely through the duct without any unnecessary 85 friction.

Valves 23 are provided whose stem heads 24 are adapted to be engaged by the car 20, as it approaches the same, to let compressed air or motive fluid in behind the car and 90 thereby impel the car forwardly, it being, of course, understood that the air pressure in advance of the car is always lower than that behind the car, due to the provision of the gates 18, which open in one direction 95 only, hence the car will be moved in the one direction only.

It will, of course, be understood that the drawings do not attempt to disclose specific details of construction but are largely diagrammatic for the purpose of illustrating the invention.

From the foregoing description taken in connection with the accompanying drawings, it is thought the construction and 105 operation of the invention will be clear to those skilled in the art.

What is claimed is:

In a system of the class described, a tunnel-way, longitudinally arranged sets of 110 rollers in the walls of the tunnel-way, a car having a nose and adapted to fit in and

- closely conform to the tunnel-way, one-way gates arranged as cut offs in the tunnel-way and adapted to be engaged and separated by the nose of the car, as it approaches the same, means tending to close the gates, and means for admitting motive fluid into the tunnel-way through the walls thereof at intervals, said means including ducts having their discharge ends arranged
- 5 for admitting the motive fluid at an inclination to the direction of travel of the car, and control devices for the several ducts,

each having operating stems projected into the tunnel-way and adapted to be opened by engagement of the nose of the car with 15 the same and held opened while the car passes the same, whereby to admit the motive fluid and cause it to impact the rear of the car as the car passes the discharge ends of the ducts, substantially as shown and 20 described.

In testimony whereof I affix my signature.

JAMES CONLON.
